UNITED STATES PATENT OFFICE.

ALBERT A. CLIVE, OF LOS ANGELES, CALIFORNIA, ASSIGNOR TO AMERICAN FIRE ALARM COMPANY, OF LOS ANGELES, CALIFORNIA, A CORPORATION OF CALIFORNIA.

CARTRIDGE FIRE-ALARM.

1,189,916.

Specification of Letters Patent. Patented July 4, 1916.

Application filed April 14, 1914. Serial No. 831,830.

To all whom it may concern:

Be it known that I, ALBERT A. CLIVE, a citizen of the United States, residing at Los Angeles, in the county of Los Angeles and 5 State of California, have invented a new and useful Cartridge Fire-Alarm, of which the following is a specification.

This invention relates to the class of fire alarms having a spring held in tension by 10 means of a fusible member and adapted through intermediate means to explode a cartridge, and thereby sound an alarm.

The invention may be carried out in various forms.

15 The accompanying drawings illustrate the invention.

Figure 1 is a perspective view of a preferred form of the invention set. Fig. 2 is a longitudinal section of the form shown in 20 Fig. 1 in the act of sounding an alarm. Fig. 3 is a view from the left of Fig. 2.

In the form shown in Figs. 1, 2 and 3, a rigid member in the form of a bar 26 is pierced at one end with an orifice 27, for 25 holding a cartridge. The opposite end is provided with a swivel screw 28 for suspending the device from a wall or ceiling.

A resilient member in the form of a spring 29 is coextending with said bar, and attached thereto by rivet 5, and at a distance 30 from the point of attachment 5 and preferably at the opposite end thereof, is provided with a hammer 30 and lug 31 respectively on opposite sides of the free end, the lug 35 being spaced from the end of the spring. A resilient catch 32 extends between the end of the spring and lug and projects, when

30 in the set position, over the end of the spring to engage with a rigid retainer shown 40 as a link 33 which is pivoted to the bar 26, and which, in the set position, holds the spring 29 retracted. A fusible element 34 is interposed between lug 31 and catch 32 to maintain restraining contact between the 45 rigid elements 26, 33 and the resilient element 29 by causing the catch to engage with and catch link 33. When the device is set for use, the fusing of element 34 will release catch 32 which in turn releases retainer 33 50 and spring 29, causing the hammer 30 to explode the cartridge.

The form shown in Figs. 1, 2, 3 is preferred for the reason that the force of the spring is normally resisted by means of the 55 catch, the fusible element 34 and the fusible

element holding means or lug 31; and the element 34 may be of comparatively large dimensions and is not subject to any shearing action which might otherwise cut off the fusible element while yet in a solid state.

60

It is noted that in the form shown, a rigid retainer as 33 in Figs. 1, 2, 3, is pivotally connected with the bar marked by the character 26 in Figs. 1, 2, and 3, and that said bar in each of the figures is held by interposition of the fusible stop, said fusible stop being marked 34 in Figs. 1, 2, 3; the interposition of said stop being indirect in Fig. 1, through the medium of the catch 32, and that the fusible member thus interpositioned maintains retaining contact between the free ends of the rigid and resilient members, and that so long as the temperature remains sufficiently low the fusible means formed of said stop serves to hold the retainer 33 in 70 position to hold the resilient and rigid members relatively retracted, and that said fusible element is effectual by its fusion to release the resilient element. One of the elements thus relatively restrained is pierced 75 with cartridge retaining holes or seats as at 27 in Figs. 1 and 2.

80

It is to be noted that in the form shown the rigid retainer as 33 is ultimately held by a fusible stop as 34 so that whenever the 85 stop melts the retainer is freed.

I claim:

1. The combination with a rigid element pierced to hold a cartridge of a resilient element coextending with the rigid element 90 and fixed to one end thereof, a hammer on the free end of the resilient element for exploding the cartridge, a retaining element interposed between the rigid and resilient elements to hold the resilient element retracted, the retaining element being pivotally connected to the rigid element, a lug on the end of the resilient member and spaced from the end thereof, a resilient catch extending between the lug and end 95 of the resilient element and projecting in the set position to engage the retaining element, and a fusible element interposed between the lug and catch to hold the catch in the set position.

100

2. A fire alarm comprising a rigid and a resilient element fastened together at one end, the rigid member being pierced to hold a cartridge, a hammer on the resilient member for exploding the cartridge, a retaining 110

- element interposed between the free ends of the rigid and resilient elements to hold the resilient element retracted, a lug on the resilient element and spaced from the end thereof, a resilient catch extending between the lug and the end of the resilient element and projecting to engage the retaining element, and a fusible element interposed between the lug and resilient catch to hold the resilient catch in position to engage the retaining element and hold the resilient element retracted.
3. In a fire alarm, the combination with a rigid bar and a coextending spring fixed to the bar at one end, the bar having an orifice for holding a cartridge, a hammer on said spring for exploding the cartridge, of a retaining link interposed between the spring and bar to hold the spring retracted, the link being pivoted to the bar, a lug on the spring and spaced from the end thereof, a resilient catch extending between the lug and spring and projecting to engage the link, and a fusible wedge interposed between the lug and catch to hold the catch in position to engage the link to hold the spring retracted.

4. In a fire alarm, the combination with a rigid bar pierced to hold a cartridge, a spring fixed at one end to the bar and provided with a hammer for exploding the cartridge, a link to retain the hammer in retracted position, a resilient catch to engage with said link, and a fusible element to hold the catch in engagement with the link, of a swivel suspension screw in the end of the rigid bar.

5. The combination with a bar having means to hold a cartridge, of a spring fixed to the bar and having means to explode the cartridge, means between the bar and spring to hold the spring retracted; yielding means to retain the retracting means in spring retracting position; a fusible element to hold the retaining means in retaining position; and means to hold the fusible means in holding position.

In testimony whereof, I have hereunto set my hand at Los Angeles, California, this 28th day of March, 1914.

ALBERT A. CLIVE.
